UNITED STATES PATENT OFFICE.

CHARLES S. WILLIAMSON AND WILLIAM H. HAZARD, OF CHICAGO, ILLINOIS; SAID HAZARD ASSIGNOR OF HIS ENTIRE RIGHT TO THE MEAD-MORRISON MANUFACTURING COMPANY, OF BOSTON, MASSACHUSETTS, A CORPORATION OF MAINE.

DUMPING APPARATUS.

1,360,607.

Specification of Letters Patent. Patented Nov. 30, 1920.

Application filed January 29, 1918. Serial No. 214,296.

To all whom it may concern:

Be it known that we, CHARLES S. WILLIAMSON and WILLIAM H. HAZARD, citizens of the United States, residing at Chicago, in 5 the county of Cook and State of Illinois, have invented certain new and useful Improvements in Dumping Apparatus, of which the following is a specification.

This invention relates to an apparatus for 10 dumping coal, ore, or the like and more particularly to a form of apparatus for picking up a car bodily and turning it over into such position that the contents will be quickly dumped therefrom.

15 Among the objects of our invention is to render possible the dumping of coal, ore, or the like from cars with much greater efficiency, and economy than heretofore known; further to increase to the maximum the simplicity of construction and operation of the 20 dumping apparatus; further to provide such apparatus that the assistance given by the counterweight to the hoisting mechanism in lifting the car will be greatly increased up to a certain point beyond which the counterweight cables will act in a much more positive manner in firmly holding the car in position in the cradle; further to pass the 25 counterweight cable through the cradle and clamping mechanism and entirely around the car whereby to give this cable free movement with relation to the cradle as the latter swings; further to provide novel means for locking the car in the cradle; further to 30 provide novel means for moving the car into engagement with the side of the cradle as the latter starts to swing, and the platform track into alinement with the main track as the cradle returns to normal position; further to 35 provide novel means for raising the clamping arms away from the car as the cradle returns to normal position; and such further objects, advantages and capabilities as will later more fully appear.

40 Our invention further resides in the combination construction and arrangement of parts illustrated in the accompanying drawings, and while we have shown therein a preferred embodiment of our invention we desire 45 the same to be considered as illustrative

only, and not as limiting the scope of our invention.

In the drawings,

Figure 1 is an end elevation of a dumping apparatus embodying our invention and 55 showing in dotted lines the cradle and car when in dumping position.

Fig. 2 is a diagrammatic view showing the cradle and car in a mid-position while being 60 swung from normal to dumping position.

Fig. 3 is a detail of the mechanism for automatically raising the clamping means away from the top of the car.

Fig. 4 is a detail view of the mechanism for moving the car toward the side of the 65 cradle.

Fig. 5 is a plan view of the end portion of the rod for sliding the car platform side- 70 wise, and the bifurcated hook just prior to engagement therewith.

75 Referring to Fig. 1 of the drawings our improved dumping device consists generally in the cradle C upon which is mounted the slidable platform or platen 1 carrying the rails 2, upon which can be rolled the car 3. The cradle C is pivotally mounted at 4 to the fixed upright support 5 and extending around the front portion of the cradle is the hoisting cable 6 which continues to the rear side of the cradle where it is suitably secured thereto at 7, and which cable passes around a hoisting drum 8 suitably operated by any desired source of motive power. By rotating the hoisting drum 8 and winding up the cable 6 it will thus be seen that the cradle C will 85 be swung about the pivot 4 into the position indicated in Fig. 1 by dotted lines. In order to assist the hoisting cables 6 in swinging the cradle C, and also to securely hold the car within the cradle when in dumping position, we have provided the counterweight cable 9 carrying at one end any suitable number of counterweights 10. This cable, as shown, passes over the sheave 11 and continues downwardly and passes through the cradle C entirely around the car 3, and is secured at its free end to the overhead frame work at 12. The cradle is provided with sheaves 13, 14 and 15 in its horizontal member as shown in Fig. 1 over the former two of which 90 95 100

sheaves the cable 9 passes when the cradle is in its normal position. After passing these sheaves the cable continues upwardly and over the sheaves 16 and between the sheaves 5 17 and 18, the latter three sheaves being carried by the clamping mechanism which comprises the member 19, and head 21 pivotally connected at 20. The head 21 is formed with a downwardly projecting extension which 10 slidably passes through the guide way 22. From this general description it will be seen that when the cradle C is being swung around the pivot 4 by means of the hoisting cables 6, this swinging will be facilitated by 15 the counterweight 10, producing an upward pull in the cable 9. As the cradle C progresses upwardly in this swinging movement the counterweight cable 9 will accommodate itself to the constantly changing position of 20 the cradle by appropriately moving over the above described sheaves in the cradle and clamping mechanism. By continuing the counterweight cable 9 through cradle C and entirely around the car 3 and securing the 25 free end of the same to a point as shown overhead, a much greater lifting effect (which will be added to the lifting force of the hoisting cable) will be produced than if the counterweight cable were merely fixedly secured 30 to the cradle. As the cradle C continues to move upwardly the clamping member 19 and head 21 finally come into contact with the top of the car, after which time the portion 60 of the hoisting cable 9 will then exert a positive pull upon the outer end of the clamping member 19, thus pressing the same against the top of the car and firmly clamping it in 35 position upon the cradle. In Fig. 2 the cradle and car are shown in a position in which the 40 car is still held by gravity within the cradle, but beyond which position the tendency will be for the car to slip out of the cradle, but which slipping is prevented by the clamping means 19 and 21, referred to above. When 45 the cradle and car reach a position shown in dotted lines in Fig. 1 the contents of the car will be dumped therefrom and the car prevented from leaving the cradle by the clamping means 19 and 21 just referred to. In this 50 extreme position it will be seen that the tendency of the counterweights 10 will be to return the cradle and car to normal position upon the paying out or unwinding of the hoisting cable 6. In following the movements of the cradle from normal to dumping 55 position it will be seen that the position of the counterweight cable 9 will be changed with relation to the sheaves. For example, in Fig. 2 it will be noted that the counterweight cable has left the sheaves 13 and 18 and has passed into engagement with the sheave 17, while in the dotted position in Fig. 1 this cable has further changed its position so that the portion 60 thereof is in engagement with the sheave 13 and the por-

tion 9 has passed into engagement with the sheave 15. This provides an extremely flexible arrangement and one which renders possible the maximum of efficiency in the operation of the clamping means 19 and 21 as well as greatly facilitating all operations of handling the entire weight of the cradle, car and its contents.

Referring to the apparatus more in detail, the cradle comprises the upright portion 30 and the horizontal portion 31 at the outer end of which is provided a plurality of suitable grooves 32, into which grooves fit the hoisting cables 6, which cables, as stated above, are secured at their ends to the upright portion of the cable at 7. As will of course be understood, the cradle will be composed of a suitable number of frame members longitudinally spaced from each other, there being preferably two end members comprising the upright 30 and horizontal portion 31, between which end members will be spaced four (or any other number desired) other frame members of a substantially similar construction. The end members just described will carry the pivotal mountings 4 and to these end members will also be secured the hoisting cables 6. The counterweight cables 9 will pass through the sheaves referred to above, and which sheaves are located in the four intermediate members just referred to. Upon the upper surface of the horizontal portion of the cradle will be mounted the transversely slideable platform or platen 1, carrying the track 2 upon which the car is supported. As coal cars and the like are often of different widths, and as it is necessary that the side of the car be in engagement with the side of the cradle prior to being clamped therein, we have provided means for sliding the car transversely upon the cradle after the same is rolled thereon. This means comprises the platform or platen 1 which is mounted on wheels 32 adapted to roll upon the upper surfaces of the cradle members. In order to effect the rolling of the wheels 32 and the consequent movement of the platform or platen and car we have provided the platen rod 33, which, as shown in Fig. 1, extends through the platform 1 and is fixed thereto, so that the platform will move laterally as this rod is moved longitudinally. In order to effect a moving of this rod in appropriate direction to move the side of the car toward the side of the cradle, we have provided at its longer end a special mechanism, shown in Fig. 4 in which it will be seen that at the outer end of this rod there is suitably journaled a roller 34 which when the cradle is in normal position contacts with the face 35 of the block 36 fixed to the upright member 5. At a slight distance above the block 36 and pivoted to the stationary member 5 is a bifurcated hook 37,

which as shown in Fig. 5 comprises the two arms 38 and 39, the outer ends of each of which is formed on its under surface with the projection 40 adapted to take over the 5 respective ends of the shaft 41, upon which the roller 34 is mounted. The shape of the projection 40 is such that when the ends of the shaft 41 move against the same from right to left (the angle or locking plate 42 not having as yet reached the end of the hook during the return of the cradle to normal position) the projection 40 will ride over the shaft 41 and cause the hook to drop into the position shown in Fig. 4, after 10 which the foot portion of the angle plate 42 will ride over the hook and hold it from rising. Secured to the side of the cradle is this angle plate 42 which is so positioned as to be closely above the upper surface of the 15 hooks 38 and 39 and when the cradle starts to swing up will hold them in engagement with the shaft 41 until the appropriate distance has been traveled through. The operation of this track sliding means is as 20 follows: Assuming that a car of maximum width has been rolled on to the track 2 (it being desirable that the sides of all cars rolled thereon amply clear the sides of the cradle in order to prevent damage of parts), 25 and that the car stands in the position shown in Fig. 1. When the cradle is started in its upper swinging movement the hooks 38 and 39 by virtue of their being held by the angle or locking plate 42 in engagement 30 with the shaft 41 will prevent the movement of the platen rod 33, the consequence of which will be to cause the track platform 1 to slide to the left (see Fig. 1) until the locking plate 42 has moved clear of the 35 hooks 38 and 39 allowing them to then swing up and release shaft 41 in the end of platen rod 33 by which time the angle of rotation will be sufficient to cause the platen to move by gravity until the side of the car 40 contacts with the side of the cradle, at which time the platen rod 33 will be free to move upward with the cradle. Upon the return of the cradle the roller 34 will strike the block 36 and again return the track 2 into 45 registry with the main track thus insuring proper registry of these tracks at all times when the cradle is in normal position. If desired, a set screw 43 may be fitted through the hooks 38 and 39 to come in contact with 50 the top of the block 36 whereby the position of these hooks with relation to the shaft 31 may be adjusted within certain limits. As the roller 34 approaches the block 36 the hooks 38, 39 will engage the shaft 41 after 55 which they will be held thus by the angle plate 42, which during further movement of the cradle toward its normal position passes closely over the upper surface of these hooks.

60 As stated above, when the cradle has

swung through a certain distance the clamping member 19 will come into engagement with the top of the car. However, in returning the cradle to normal position it is found desirable to provide means for forcibly elevating the face 44, of the head 21, away 70 from the car. In order to effect this, we have provided a mechanism which will now be described. As stated above, the head 21 of the clamping means is formed with an extension slidably passing downwardly through the guide ways 22, which extension is designated at 45 in Fig. 3, and has pivotally connected at its lower end one or more rods 46 which carry at the lower ends the roller 47 mounted on the shaft 48. Pivotally connected to the lower end of the rods 46 and 49 is a transversely extending brace rod 50, which at its outer end is pin connected at 51 to a bracket 52 or otherwise suitably secured to the forward lower corner of the 75 cradle. Referring to Fig. 1, there is provided directly below the roller 47 and preferably embedded in the concrete, or fastened in any suitable manner to the stationary 80 part of the frame work, the cam rail 53, which, as shown, is curved upwardly near its outer end at 54. When the cradle with its load is started on its swinging movement it will be seen that the head 21 of the clamping means will descend until it contacts with the upper edge of the car, the roller 47 in the meantime having been carried by the cradle to the right and away from the cam plate 53, which movement to the right, due 85 to the change in angularity of the rod 46 with relation to the cam plate 53, together with the slidable mounting of the extension 45 in the guideway 22, permits the rod 46 and head 21 to descend. After the car has 90 been dumped and the cradle is being returned to normal position, the head 21 still being in contact with the upper surface of the car the roller 47 will, due to this extended position, strike the cam rail 53 at some point adjacent the portion 54, and as obvious, due to the change in angularity of the parts, the roller 47 during its travel from the point 54 to its normal position shown in 95 Fig. 1 will cause an upward thrust on the rod 46 and extension 45 and thus raise the 100 head 21 away from the top of the car. Any bending of the rod 46 will be prevented by the brace-rod 50. 105 From the above description it will be seen that when a loaded car has been rolled on to the platform 1 and the cradle started on its swinging movement the platen rod 33, by virtue of being held through a short period of time by the hooks 38 and 39 will move the car sidewise until the hooks are released from shaft 41. At this point (or immediately thereafter) the inclination of the cradle will be such as to permit gravity to 110 then move the platform and car through any further distance necessary to cause the side 115 120 125 130

of the car to contact with the side of the cradle. After the cradle has swung through a further distance the head 21 will then drop into clamping position upon the inner 5 upper edge of the car. As the swinging is continued, the lower face 50 of the clamping member 19 will then come into engagement with the outer edge of the car and the clamping means will from then on to the end of 10 the swinging movement firmly clamp the car into position in the cradle. Upon the return of the cradle to its normal position a point will be reached at which the surface 50 of the clamping member 19 will be raised away 15 from the car, but the head 21 will remain in contact therewith until the roller 47 contacts with the cam plate 53, after which this head will be raised free of the car. Just prior to the cradle reaching its normal position the 20 roller 34 will strike the block 36 to push the platform track and main track into registry. Since the counterbalance cable slidably passes through the cradle and entirely around the car a much greater lifting effect 25 will be produced thereby than if this cable were rigidly secured to the cradle, this being caused by the fact that there are two active portions to the counterweight cable which when multiplied by their lever arms 30 will together produce a greater turning moment that would a single cable (rigidly fixed to the cradle) when multiplied by its lever arm. This arrangement of counterweight cable also makes possible the novel 35 form of locking means described above, and produces a much more flexible, efficient, simple and economical arrangement than would be possible were such cable fixedly secured to the cradle.

40 We claim:

1. In apparatus of the class described a swinging cradle adapted to carry a car thereon, a hoisting cable fixedly secured at one end to said cradle, and a counterweight 45 cable passing through said cradle beneath and over said car to substantially encompass the same and secured at the end opposite the counterweight to a point independent of the cradle.

50 2. In apparatus of the class described a swinging cradle adapted to carry a car thereon, sheaves on said cradle, a hoisting cable fixedly secured at one end to said cradle, a counterweight cable passing over 55 said sheaves beneath and over said car to substantially encompass the same whereby to freely hold the cradle in the bight of said last mentioned cable, said counterweight cable being secured at the end opposite the 60 counterweight to a point independent of the cradle.

65 3. In apparatus of the class described a cradle adapted to swing a loaded car into substantially inverted position, means for swinging said cradle and car, and a counter-

weight cable secured at its free end to a point independent of said cradle and slidably passing through said cradle beneath and over said car to substantially encompass the same. 76

4. In apparatus of the class described a cradle adapted to swing a loaded car into substantially inverted position, means for swinging said cradle and car, and a counterweight cable secured at its free end to a 75 point independent of said cable and slidably passing through said cradle beneath and over said car to substantially encompass the same, and means operated by said counterweight cable for clamping the car in the 80

5. In apparatus of the class described a cradle adapted to swing a loaded car into substantially inverted position, means for swinging said cradle, a counterweight cable 85 passing through said cradle beneath and over said car to substantially surround the same, means for clamping said car in said cradle, and means for automatically raising said clamping means away from said 90 car upon the return of said cradle to normal position.

6. In apparatus of the class described a cradle adapted to swing a loaded car into substantially inverted position, means for 95 swinging said cradle, a counterweight acting upon said cradle, a transversely slidable track on said cradle for supporting the car, means for clamping said car in the cradle, means for automatically raising said clamping 100 means away from said car upon the return of the cradle to normal, means for holding said track stationary during the initial swinging movement of said cradle, and means for releasing said holding means 105 when the cradle has moved through a pre-determined distance.

7. In apparatus of the class described a cradle adapted to swing a loaded car into substantially inverted position, means for 110 swinging said cradle, a counterweight cable passing through said cradle and entirely around said car to substantially encircle the same, a transversely slidable track on said cradle, means for automatically sliding said 115 track to move said car toward the side of said cradle as said cradle starts to swing whereby to bring the car into proper clamping position, and means to automatically clamp said car in said cradle upon the continuation of said swinging movement. 120

8. In apparatus of the class described a cradle adapted to swing a loaded car into substantially inverted position, means for swinging said cradle, a counterweight cable 125 passing through said cradle and entirely around said car to substantially encircle the same, a transversely slidable track on said cradle, means for automatically sliding said track to move said car toward the side of 130

5 said cradle as said cradle starts to swing whereby to bring the car into proper clamping position, and means to automatically clamp said car in said cradle upon the continuation of said swinging movement, and means to automatically raise said clamp away from said car upon the return of the cradle to normal position.

9. In apparatus of the class described a 10 cradle adapted to swing a loaded car into substantially inverted position, means for swinging said cradle, a counterweight cable passing through said cradle and entirely around said car to substantially encircle the 15 same, a transversely slidable track on said cradle, means for automatically sliding said track to move said car toward the side of said cradle as said cradle starts to swing whereby to bring the car into proper clamping 20 position, and means to automatically clamp said car in said cradle upon the continuation of said swinging movement, means to automatically raise said clamp away from said car upon the return of the cradle 25 to normal position, and means for returning said track into registry with the main track as said cradle returns to normal position.

10. In a dumping apparatus a pivotally 30 mounted cradle adapted to swing a car into substantially inverted position, means to swing said cradle, a counterweight cable passing through said cradle, beneath and over said car to substantially encircle the 35 same, and means to clamp said car into said cradle, said last mentioned means being actuated by the part of said counterweight cable, which passes over said car.

11. In a dumping apparatus, a pivotally 40 mounted cradle adapted to swing a car into substantially inverted position, means to swing said cradle, a transversely slidable platform on said cradle, a rod fixed to said platform and projecting through said cradle, and means for holding said rod stationary during the initial swinging movement of the cradle, whereby to cause the side of the cradle to move toward a car on the platform.

50 12. In a dumping apparatus, a supporting structure having a cradle pivotally mounted therein, means for swinging said cradle, a transversely slidable platform on said cradle adapted to support a car, and means for positively holding said platform stationary during the initial movements of said cradle, whereby to cause the side of the cradle to move toward the side of the car on the platform.

60 13. In a dumping apparatus a cradle, a transversely slidable platform adapted to support a car on said cradle, a rod extending transversely from and fixed to said platform, stationary supports to which said cradle is pivoted, a pivotally mounted hook

independent of said cradle and adapted to engage the end of said rod to hold the same against movement as the cradle swings through a short distance whereby to move the car toward the side of the cradle. 70

14. In a dumping apparatus a cradle adapted to swing a loaded car into substantially inverted position, a locking means having an extension slidably mounted in said cradle, a rod pivotally mounted on said extension and having a roller at its opposite end, a stationary cam-rail below said cradle, the relation between the cam-rail and roller being such that as the cradle swings to normal position the roller will come into contact with and move along said cam-rail whereby to lift said clamping means away from said car, and means to prevent bending of said rod when said roller strikes the cam plate. 80

15. In a dumping apparatus a cradle adapted to swing a loaded car into substantially inverted position, a locking means having an extension slidably mounted in said cradle, a rod pivotally mounted on said extension and having a roller at its opposite end, a brace rod pivotally connected at one end to said first mentioned rod and at its opposite end to the cradle, a stationary cam-rail below said cradle, the relation between the cam-rail and roller being such that as the cradle swings to normal position the roller will come into contact with and move along said cam-rail whereby to lift said clamping means away from said car. 90

16. In a dumping apparatus a supporting structure, a cradle pivotally mounted in said supporting structure and adapted to swing a loaded car into substantially inverted position, means for swinging said cradle, a transversely slidable platform on said cradle adapted to support said car, a rod fixed to said platform and extending rearwardly through said cradle, a lateral projection on the rear end of said rod, a hook mounted independently of said cradle and constructed to engage said projection to hold said rod and platform in a substantially stationary position as said cradle starts to swing whereby to cause the side of said cradle to move toward the side of said car, and means for releasing said hook from said projection when the cradle has swung through a predetermined distance. 110

17. In a dumping apparatus a supporting structure, a cradle pivotally mounted in said supporting structure and adapted to swing a loaded car into substantially inverted position, means for swinging said cradle, a transversely slidable platform on said cradle adapted to support said car, a rod fixed to said platform and extending rearwardly through said cradle, a lateral projection on the rear end of said rod, a hook movably mounted independently of said cradle and 120

constructed to engage said projection till released, and a projecting lug secured to said cradle to extend over said hook respectively whereby to hold said rod against movement 5 as the cradle starts to swing and to release said hook from said rod when the cradle has swung through a predetermined distance.

18. In apparatus of the class described a cradle adapted to swing a loaded car into 10 substantially inverted position, a platform slidably mounted on said cradle and carrying a track to support said car, a rod fixed to said platform and extending to the rear of said cradle, a bumping block against 15 which the end of said rod contacts while the cradle is being returned to normal position to bring said track in registry with a main track, a pivoted hook adapted to engage and hold the rear end of said rod while the 20 cradle starts to swing outwardly, said block and said hook being both mounted independently of said cradle, a projecting lug fixed to said cradle and extending over said hook to hold the same in engagement with 25 said rod to hold said platform and car sub-

stantially stationary while the cradle is starting to swing and adapted to move clear of said hook and permit it to disengage said rod when the cradle has swung through a predetermined distance, after which the 30 platform and car will move by gravity till the side of the car comes in contact with the side of the cradle.

19. In a dumping apparatus, a supporting structure having a cradle pivotally 35 mounted therein, means for swinging said cradle, a transversely slid able platform on said cradle adapted to support a car, means for positively holding said platform stationary during the initial movements of said 40 cradle, whereby to cause the side of the cradle to move toward the side of the car on the platform, and means for releasing said holding means when said cradle has moved through a predetermined distance.

In witness whereof, we hereunto subscribe our names to this specification.

CHARLES S. WILLIAMSON.
WILLIAM H. HAZARD.
